SOLE PRESSING MACHINE

Sidney J. Finn, Beverly, Mass., assignor to United Shoe Machinery Corporation, Borough of Flemington, N. J., a corporation of New Jersey

Application October 5, 1938, Serial No. 233,381

23 Claims.

(Cl. 12—33)

This invention relates to machines for pressing soles on shoe bottoms and is illustrated herein as embodied in a machine for cement attaching soles to shoes.

5 Objects of the invention are to provide in a sole pressing machine improved means arranged to permit a sole with a heel attached thereto, forming a complete sole and heel unit, to be pressed against a shoe bottom to effect its permanent or temporary attachment thereto, and to provide improved mechanism for relatively positioning the shoe and the sole and heel unit.

To the accomplishment of these objects the invention provides, in accordance with one of its 15 features, improved means for engaging the shank portion only of a sole having a heel attached thereto, said means resting on a supporting pad and being arranged also to engage the full height of the breast of the heel on the sole and heel unit. As herein illustrated, the shank engaging means comprises an auxiliary pad of resilient material which is substantially wedge shaped in longitudinal section with the thick portion of the wedge adjacent to the breast of the heel, 20 the rear end wall or surface of the auxiliary pad being of sufficient size transversely of the supporting pad to engage the breast of the widest heel to be operated upon at the opposite corners thereof. As illustrated, the auxiliary pad is pivotally connected to the forward end of a flat member or plate arranged to slide longitudinally of the supporting pad, a spring being provided for constantly urging the auxiliary pad and plate rearwardly of the supporting pad. The plate 25 acts to hold the auxiliary pad on the supporting pad and also acts as a support for the tread surface of the heel during the pressing operation.

In accordance with another feature of the invention improved means is provided for relatively positioning the shoe and the sole and heel unit lengthwise, this means, as herein illustrated, comprising a heel gage arranged for sliding movement lengthwise of the supporting pad and carrying a shoe gage for determining the position of the heel end of the shoe when the heel gage is engaging the heel. Means is provided for effecting relative adjustment of the heel gage and shoe gage and further means is provided for maintaining the gages in any position into which they may be moved lengthwise of the supporting pad.

With the above and other objects and features in view, the invention will now be described in connection with the accompanying drawings and will thereafter be pointed out in the claims.

55 In the drawings,

Fig. 1 is a side elevation of a machine embodying the present invention;

Fig. 2 is a view similar to Fig. 1 of a portion of the machine with parts broken away and in section; and

Fig. 3 is a plan view of the mechanism shown in Fig. 2.

The invention is illustrated herein by way of example as embodied in a sole pressing or attaching machine of the type disclosed in Letters 10 Patent of the United States No. 2,047,185 granted July 14, 1936, on an application filed in the name of Milton H. Ballard et al. As disclosed in the patent referred to the machine is provided with a plurality of pad boxes 10 mounted on a rotary 15 turret or table 12 (Fig. 1) arranged to rotate intermittently to present each pad box in turn at an operating station. As herein illustrated, the pad boxes are of the type disclosed in Letters Patent of the United States No. 2,063,041, granted 20 December 8, 1936, on an application filed in the name of Lloyd G. Knowles and are particularly adapted for operating upon large shoes such as men's shoes. The machine is also provided, opposite each pad box, with pressure applying abutments 14 and 16 for engaging respectively the forepart of a shoe A and the heel portion of a last B in the shoe and applying pressure thereto, power operated means being provided for moving the abutments toward and away from the shoe. 30

As disclosed in the Knowles patent each pad box 10 is provided at its forepart with a plurality of sole gages 18 and 20 arranged to engage the opposite edge faces of a sole positioned by an operator on a pad in the pad box and arranged 35 to become locked upon engagement with the sole. The sole gages 20, as herein illustrated, carry shoe gages 22 (Fig. 1) against which the shoe is placed when it is mounted on the sole so that its forepart will be properly positioned relatively 40 to the sole. At its rear or heel end the pad box carries two sets of equally and oppositely movable heel positioning gages 24 and 26, the gages 24 being normally arranged to engage the opposite edge faces of the sole on the pad and the gages 26 45 being arranged to engage the opposite sides of the heel portion of the shoe and position it laterally of the sole. The sets of gages 24, 26 are operated respectively by transverse slides 28 and 30, the slide 28 being actuated by a treadle (not shown) and the slide 30 by a swinging frame member 32 (Fig. 1) which carries the pressure applying abutments 14, 16 and is connected to the slide 30 by a lever 34 and intermediate connections 36, 50 55

as fully disclosed in the Knowles patent mentioned above.

- The gages 24 and 26 and their operating mechanisms, including the slides 28 and 30, are mounted in a plurality of castings 38 pivotally supported at 40 on a horizontal member 42, the latter being adjustably secured by a wing nut 44 to a shelf 46 extending horizontally from a vertical slide 48 arranged to travel in ways formed on the opposite sides of the pad box. The slide 48 is yieldingly supported in its uppermost position on the pad box by springs 50 so that it can yield under pressure applied to the sole and shoe by the abutments 14 and 16.
- 15 The present invention, as indicated above, is particularly concerned with the cement attachment to shoes of outsoles to which heels have been previously attached to form complete sole and heel units. Accordingly, the pad box 10 is provided with a flexible or deformable pad 52, herein shown as a hollow vessel of rubber, filled with a fluid 54 (Fig. 2) such as water, and having its sole engaging surface molded to conform substantially to the shape of the bottom of a last or shoe. The pad 52 is provided at its rear portion with a relatively narrow longitudinal depression or slot 56 formed when the pad is molded, this depression being preferably located at the central portion of the pad and extending to its heel end.
- 20 Resting on the upper surface of the pad 52 is a separate auxiliary pad 58 having an upper surface 60 substantially complementary in shape to the shank portion of a shoe and adapted to engage only the shank portion of a sole S placed 25 on the pad 52, the sole having a heel H assembled thereon which is attached to the sole in the usual manner by cement or nails, or both, to form a complete sole and heel unit prior to the attachment of the sole to the shoe bottom. The 30 auxiliary pad 58 is preferably composed of resilient material such as rubber or a composition thereof and, as shown in the drawings, is substantially wedge shaped from front to rear with the thick end of the wedge at the rear. The 35 rear edge of the pad 58 is straight in plan view and the pad has a forward edge that is curved transversely to approximate the shape of the ball or break line at the forward end of the shank portion of either a right or left shoe, the shoe 40 in the present case being a right shoe. At its thick end the auxiliary pad 58 has an upstanding surface 62 of sufficient width to engage the breast of the largest heel to be operated upon at the opposite corners of said breast and the 45 pad is of sufficient thickness at its rear portion so that the vertical surface 62 will be as high as, or slightly higher than, the heels on the usual run of men's shoes, thereby enabling this surface to engage the breast of the heel from 50 the tread surface of the outsole to the tread surface of the heel.
- The auxiliary pad 58 is provided near the lower side of its rear portion with a horizontal cut or slot 64 which produces a relatively thin lower 55 layer or flap 66 extending across the full width of the pad. It is also provided at its opposite side walls with depressions 68 and 70 the purpose of which will be explained hereinafter. Riveted to the upper side of the lower flap 66 60 adjacent to its rear end is a thin plate 72 to which is pivotally secured by a shoulder screw 74 a flat plate 76 which extends rearwardly beyond the back wall of the pad box 10 and rests at its rear portion upon a horizontal supporting 65 plate 78 provided with a central slot 80, the

plate 78 being rigidly secured to the upper end of the slide 48 by screws 82. The slide 43 and the upper end of the rear wall of the pad box 10 have formed in their central portions horizontal slots 84, as shown in Figs. 1 and 2. Although the thick end of the wedge shaped pad 58, as pointed out above, is preferably made thick enough to engage the full height of the breasts of the usual run of heels, it is possible to increase the thickness of this portion of the pad 58 is necessary for extremely high heels by inserting wedge shaped pieces of rubber in the cut or slot 64.

The rear portion of the plate 76, as shown in Fig. 3, is curved rearwardly to approximate the semi-circular shape of the back end of a heel and the plate is arranged to slide longitudinally of the pad box between the opposite side walls of the box in the plane of the upper surface of the pad 52. The plate is prevented from being raised above the side walls of the pad box by gibs 90, 92 secured to the opposite sides of the pad box by screws 94 and arranged to overlie the opposite edge portions 86, 88 of the plate. The depressions 68, 70 in the auxiliary pad 58 provide clearance for the gibs 90, 92 as the pad 58 is moved rearwardly with the plate 76. Near its forward end and substantially on the longitudinal median line of the pad box the plate 76 carries a downwardly projecting pin 96 (Fig. 2) to which is fastened a rearwardly extending tension spring 98 which is secured at its other end to a downwardly extending pin 100 mounted in the rear end of the supporting plate 78, this latter plate being curved at its rear portion similarly to the plate 76. The spring 98 is located in the slot 56 in the pad 52 and it passes through the slots 84 (Fig. 1) in the slide 48 and pad box 10 and tends constantly to urge the plate 76 and the auxiliary pad 58 rearwardly toward the heel end of the pad 52. The rearward limit of movement of the plate 76 is determined by a shoulder or head on the pin 100 which extends into a slight depression or groove 102 formed in the lower surface of the rear portion of the plate 76, the shoulder being arranged to engage the forward end of this groove when the plate is in its rearward position.

It will be seen from the above that the auxiliary pad 58 and the flat plate 76 are constantly urged rearwardly by the spring 98 but they may be moved forwardly in the plane of the upper surface of the pad 52 against the tension of the spring. Moreover, the pad 58 may pivot laterally of the pad box relatively to the plate 76 about the screw 74 so that it may adjust itself automatically to the transverse angle of the breast of the heel which the vertical surface 62 of the pad is arranged to engage. In addition to the foregoing the auxiliary pad and plate 76 may move heightwise of the pad box with the upper surface of the pad 52 as that surface is deformed under pressure. In placing the sole S with the assembled heel H on the pad 52, the operator engages the vertical surface 62 of the auxiliary pad 58 with the breast of the heel and moves the sole and heel unit forwardly until the ball line of the sole is located in substantially the proper position relatively to the supporting pad 52. During this action the pad 58 is moved forwardly in front of the heel against the tension of the spring 98 into a proper position relatively to the pad 52. The pad 58 is also permitted by the pivotal connection 74 referred to to adjust itself laterally to the transverse angle 75.

of the breast of the heel. After the operator has located the sole and heel unit on the pad as described, he depresses a treadle of the machine to operate the forepart gage mechanism 5 18 and 26 and to bring the forepart gages into engagement with the opposite edge faces of the sole, after which the gages become locked to position the forepart shoe gages 22 properly for locating the forepart of the shoe relatively to the sole.

In addition to the heel gages 24 and 26, which are arranged to locate the heel portions of the sole and shoe relatively to each other laterally of the pad 52, the present invention further provides gage mechanism for positively determining the proper position of the shoe longitudinally of the sole and heel unit. As herein illustrated, this mechanism comprises a slide 104 arranged for movement longitudinally of the pad box in a T-slot 106 formed in the intermediate casting of the group of castings 38, the slide 104 projecting downwardly and forwardly at its forward end, as best shown in Figs. 1 and 2, to form a heel gage 108 adapted to engage the back end of the heel H and thereby position the slide lengthwise of the pad 52 relatively to the sole and heel unit on the pad. Secured in a horizontal slot 110 formed in the upper surface of the slide 104 is a right angle member 112, this member being secured in the slot by a screw 114 which extends through a lower slot 116 in the slide 104 and thus permits the member 112 to be adjusted longitudinally of the pad relatively to the slide 104 and gage 108.

The upstanding portion of the member 112 is provided with a vertical slot 118 through which extends a screw 120 which secures to the member 112 a shoe gage 122 provided on its back surface with rearwardly extending ribs 124, as shown in Fig. 3, which overlap opposite sides of the member 112 and thus prevent the gage 122 from turning on the screw 120. The gage 122 is, of course, adjustable heightwise on the member 112 by reason of the slot 118.

It will be seen from the foregoing that the lower gage 108 may be moved forwardly into engagement with the back end of the heel H of the sole and heel unit resting on the pad, thereby positioning the shoe gage 122 in the proper position for locating the shoe longitudinally of the sole and heel unit. In order that the heel gages 108, 122 will be maintained in their operative position after the gage 108 has been moved by the operator into engagement with the heel, friction means is provided for retaining them in any position into which they may be moved. As shown in Fig. 3, this means comprises a spring pressed plunger 126 mounted in a horizontal hole formed in the intermediate casting 38 referred to and urged constantly toward the slide 104 by a compression spring 128, the spring 128 being retained in the casting by a screw 130.

In the operation of the mechanism comprising the present invention, the operator places the sole and heel unit on the pad 52 after the attaching surface of the unit has been prepared for cement attachment to the shoe bottom and he locates the unit in the desired position longitudinally of the pad, thereby moving the auxiliary pad 58 longitudinally into a position to engage only the shank portion of the sole forwardly of the heel and to cause the vertical surface 62 of the pad to engage the breast of the heel. He then actuates the forepart sole gages 18, 20 to bring them into engagement with the sole and to

position the shoe gages 22 for receiving the shoe. He next places the shoe A upon the sole and heel unit and moves the heel gage 108 forwardly into engagement with the back end of the heel H, thereby positioning the shoe gage 122 for 5 locating the shoe longitudinally of the sole and heel unit. As described in the Knowles patent, when the operator actuates the forepart gages he also, by the same treadle movement, actuates the heel sole gages 24 which, in the present 10 instance, are arranged to engage the heel H instead of the sole and position the rear portion of the heel and sole unit laterally of the pad 52. The operator next moves the swinging frame member 32 forwardly to swing the pressure applying abutments 14 and 16 into operative position over the shoe A and the last B in the shoe and, by this movement of the swinging frame through the connections 34, 36 referred to, he operates the transverse slide 30 to actuate the 15 shoe gages 26 which thereupon position the heel portion of the shoe laterally of the pad relatively to the sole and heel unit. After the shoe and the sole and heel unit have been thus positioned the operator actuates the power mechanism of the machine to cause the abutments 14 and 16 to descend and press the shoe and the sole and heel unit forcibly against the pads 52 and 58, thereby causing the sole and heel unit to become permanently attached or, if desired, 20 temporarily attached to the shoe bottom.

The pad 52 will, of course, become deformed under the sole attaching pressure and its upper surface will be moved downwardly by the shoe and the sole and heel unit. As stated above, the 25 auxiliary pad 58 and the flat plate 76 will likewise move downwardly between the side walls of the pad box, the plate being maintained in a substantially horizontal position by its engagement with the lower plate 78, thereby causing 30 pressure to be applied to the entire tread surface of the heel H and, through the heel, to the heel portions of the sole and shoe to effect a cement attachment of these portions to each other which is as strong as the cement attachment between 35 the forepart and shank portions of the shoe and the sole and heel unit, which portions are directly engaged respectively by the supporting pad 52 and the auxiliary pad 58.

Having thus described my invention, what I 50 claim as new and desire to secure by Letters Patent of the United States is:

1. A device for applying pressure to soles and shoes comprising a pad for supporting a shoe and a sole having a heel attached thereto, and 55 an auxiliary pad mounted on said supporting pad for pivotal movement relatively thereto and having an upper surface adapted to engage the shank portion only of the sole and an upstanding surface arranged to engage the breast of the heel 60 on the sole, said upstanding surface being of sufficient width to engage the opposite corners of the breast of said heel.

2. A device for applying pressure to soles and shoes comprising a pad for supporting a shoe and 65 a sole having a heel attached thereto, a separate pad resting on the supporting pad and having an upper surface adapted to engage the shank portion of the sole, and means arranged normally to urge said separate pad toward the heel end 70 of said supporting pad.

3. A device for applying pressure to soles and shoes comprising a flexible pad for supporting a shoe and a sole having a heel attached thereto, an auxiliary pad resting on the supporting pad 75

and having an upper surface shaped to engage only the shank portion of the sole and having a rear surface adapted to engage the breast of the heel, and non-flexible means connected to said auxiliary pad for engaging the tread surface of said heel.

4. In a sole pressing machine, the combination of a pad, means for pressing a shoe and a sole with a heel assembled thereon against the pad, 10 and an auxiliary pad resting on the first-named pad and movable laterally thereof for engaging the shank portion of the sole, said auxiliary pad having a rear surface adapted to engage the breast of the heel.

15. 5. In a sole pressing machine, the combination of a flexible pad having a surface for supporting a sole and shoe, means for pressing a shoe and a sole with a heel attached thereto against said pad, and a separate pad of resilient material resting on said flexible pad and movable 20 in the plane of the supporting surface of said flexible pad for engaging the shank portion of the sole, said auxiliary pad having a rear up-standing surface wider than the heel and adapted 25 to engage the breast of said heel.

6. In a sole pressing machine, the combination of a pad, means for pressing a shoe and a sole with a heel assembled thereon against the pad, and an auxiliary pad resting on the first-named pad and having a sole engaging surface 30 substantially complementary to the shank portion of the sole, said auxiliary pad being movable longitudinally of the first-named pad in the plane of the upper surface of said first-named pad.

35. 7. In a sole pressing machine, the combination of a fluid filled deformable pad, means for pressing a shoe and a sole with a heel attached thereto against said fluid filled pad, an auxiliary pad of solid but resilient material resting on the 40 deformable pad and movable relatively thereto, said auxiliary pad having a surface thereon for engaging the shank portion only of the sole and another surface for engaging the breast of the heel, and means for normally holding said auxiliary pad in a predetermined position on said fluid filled pad.

8. In a sole pressing machine, the combination of a pad, means for pressing a shoe and a sole with a heel attached thereto against said pad, an auxiliary pad resting on the first-named pad and having a sole engaging surface adapted 50 to engage the shank portion of the sole across its full width forwardly of said heel, and means arranged constantly to urge the auxiliary pad toward the rear portion of said first-named pad.

55. 9. In a sole pressing machine, the combination of a flexible pad, means for pressing a shoe and a sole with a heel attached thereto against said pad, an auxiliary pad resting on the flexible pad and having a surface adapted to engage only the shank portion of the sole and an adjacent surface adapted to engage the breast of said heel, and means for permitting angular movement of said auxiliary pad laterally of said flexible pad.

70. 10. In a sole pressing machine, the combination of a flexible pad, means for pressing a shoe and a sole with a heel attached thereto against said pad, an auxiliary pad supported by said flexible pad and arranged to engage the shank portion only of the sole forwardly of said heel, means for holding said auxiliary pad on the flexible pad, and means arranged constantly to urge the auxiliary pad toward the rear end of said flexible pad.

11. In a sole pressing machine, the combination of a flexible pad for supporting a sole and shoe, means for pressing the shoe and a sole with a heel attached thereto against said flexible pad, an auxiliary pad of resilient material resting on the supporting pad and arranged to engage the shank portion of the sole, said auxiliary pad having a rear wall adapted to engage the breast of the heel on the sole, and non-flexible means pivotally connected to said auxiliary pad for engaging the entire tread surface of said heel. 5

12. In a sole pressing machine, the combination of a fluid filled pad for supporting a sole and shoe, means for pressing a shoe and a sole having a heel attached thereto against said pad, 15 an auxiliary wedge shaped pad resting on the fluid filled pad and arranged to engage only the shank portion of the sole and the breast of the heel, and means for urging the auxiliary pad rearwardly of the fluid filled pad. 20

13. In a sole pressing machine, the combination of a pad for supporting a sole and shoe, means for pressing the shoe and a sole having a heel attached thereto against the pad, an auxiliary pad resting on the supporting pad and arranged to engage the shank portion of the sole forwardly of the heel, said auxiliary pad having a rear wall movable laterally and of sufficient width to engage the breast of the heel on the sole at the opposite corners of the breast of said 30 heel, a spring tending constantly to urge the auxiliary pad toward the heel end of the supporting pad, and a flat member connected to said auxiliary pad for engaging the tread surface of the heel. 35

14. In a sole pressing machine, the combination of a pad for supporting a shoe and a sole with a heel attached to the sole, an auxiliary pad for engaging the shank portion only of the sole forwardly of the heel, and gage mechanism arranged to engage the shoe and the heel on the sole and position the shoe and sole relatively to each other lengthwise of the supporting pad. 40

15. In a sole pressing machine, the combination of a pad for supporting a shoe and a sole with a heel attached thereto, an auxiliary pad resting on the supporting pad and arranged to engage the shank portion of the sole and the breast of the heel, a gage movable into engagement with said heel, and means carried by said gage for determining the position of the shoe relatively to the sole. 45

16. In a sole pressing machine, the combination of a pad for supporting a shoe and a sole with a heel assembled thereon forming a complete sole and heel unit, means for pressing the shoe and the sole and heel unit against the pad, an auxiliary pad resting on the supporting pad and arranged to engage only the shank portion of the sole forwardly of the heel, said auxiliary pad having an upstanding wall adapted to engage the breast of the heel, a gage rearwardly of the supporting pad movable into engagement with the rear end of the heel, and another gage carried by the heel gage for determining the longitudinal position of the shoe relatively to the sole and heel unit. 50

17. In a sole pressing machine, the combination of a pad for supporting a shoe and a sole with a heel attached thereto, means for pressing the shoe and sole against the pad, an auxiliary pad resting on the supporting pad and adapted to engage the shank portion only of the sole, means tending constantly to move the auxiliary pad toward the heel end of the supporting pad, a gage 55

movable lengthwise of said supporting pad for engaging the back portion of the heel on the sole, another gage carried by the heel gage for engaging the heel end of the shoe and determining its lengthwise position relatively to the sole, and means for maintaining said gages in the positions into which they are moved.

18. In a sole pressing machine, the combination of a pad for supporting a shoe and a sole with a heel attached thereto, means for pressing the sole and shoe against said pad, an auxiliary pad resting on the supporting pad and having an upper surface adapted to engage the shank portion of the sole and a rear surface adapted to engage the breast of the heel, a gage movable lengthwise of the pad for engaging the back of the heel on the sole, another gage carried by the heel gage for determining the longitudinal position of the shoe relatively to the sole and heel, and means whereby said gages may be adjusted relatively to each other.

19. In a sole pressing machine, the combination of a pad for supporting a shoe and a sole with a heel attached to the sole, means for pressing the sole and shoe against said pad, an auxiliary pad resting on the supporting pad and having an upper surface adapted to engage the shank portion of the sole and a rear surface adapted to engage the breast of the heel on the sole, a gage movable lengthwise of the supporting pad for engaging the back of the heel on the sole, another gage carried by the heel gage for determining the lengthwise position of the shoe relatively to the sole and heel, spring pressed means for automatically maintaining said gages in the lengthwise positions into which they are moved, and means for relatively adjusting the gages lengthwise of the supporting pad.

20. In a sole pressing machine, the combination of a pad for supporting a shoe and a sole with a heel attached thereto, means for pressing the shoe and sole against the pad, a resilient auxiliary pad resting on said supporting pad and movable relatively thereto, said auxiliary pad having an upper surface adapted to engage the shank portion only of the sole and a rear upstanding surface adapted to engage the breast of the heel, spring means tending constantly to move the auxiliary pad toward the heel end of the supporting pad, means connected to said auxiliary pad for engaging the tread surface of the heel, the connection between said means and the auxiliary pad permitting pivotal movement of said auxiliary pad laterally of the supporting pad, a gage movable lengthwise of the supporting pad and arranged to engage the back of the heel, another gage carried by the heel gage for determining the lengthwise position of the shoe relatively to the sole and heel, and a plurality of gages at the forepart of the supporting pad for relatively positioning the foreparts of the sole and shoe.

21. In a sole pressing machine, the combination of a pad for supporting a shoe and a sole with a heel attached thereto, means for pressing the shoe and sole against the pad, an auxiliary pad resting on said supporting pad and movable relatively thereto, said auxiliary pad having an upper surface adapted to engage the shank portion only of the sole and a rear upstanding surface adapted to engage the breast of the heel, a spring tending constantly to move the auxiliary pad, means connected to said auxiliary pad for engaging the tread surface of the heel, the connection between said means and the auxiliary pad permitting pivotal movement of said auxiliary pad laterally of the supporting pad, a gage movable lengthwise of the supporting pad and arranged to engage the back of the heel, another gage for determining the lengthwise position of the shoe relatively to the sole and heel, and a plurality of gages for relatively positioning the shoe and the sole and heel laterally of the supporting pad.

22. In a sole pressing machine, the combination of a pad for supporting a shoe and a sole with a heel attached thereto, an auxiliary pad resting on said supporting pad and movable relatively thereto, said auxiliary pad being arranged to engage the shank portion only of the shoe, a member connected to said auxiliary pad for engaging the tread surface of the heel on the sole, spring means tending constantly to urge the auxiliary pad and said member toward the heel end of the supporting pad, and means for preventing movement of said member laterally of the supporting pad but permitting lengthwise and heightwise movement of said member relatively to said supporting pad.

23. In a sole pressing machine, the combination of a pad box, a pad in the box having a surface thereon for supporting a shoe and a sole with a heel attached thereto, said surface being deformable heightwise of the pad box under pressure, an auxiliary pad resting on said deformable surface and movable relatively thereto, said auxiliary pad having an upper surface adapted to engage the shank portion only of the sole and an upstanding surface adapted to engage the breast of the heel, a flat member connected to said auxiliary pad and arranged to engage the entire tread surface of the heel, and a spring tending constantly to urge said auxiliary pad and said flat member toward the heel end of the supporting pad, said flat member being prevented by the pad box from movement laterally of the supporting pad, thereby permitting only lengthwise bodily movement of the auxiliary pad relatively to said supporting pad, both the auxiliary pad and said member being movable heightwise of the pad box with the supporting pad.

SIDNEY J. FINN.
